Garrettson Smith, Henry Brown & Samuel H. Sailor of Philadelphia Pa.
Assignors to
Alex² Small and E.G. Smyder of York Pa.
Letters Patent No 974. Dated Jan. 5th 1858.

The schedule referred to in these Letters Patent and making part of the same.

To all whom it may concern.

Be it known that we Garrettson Smith
Henry Brown, and Samuel H. Sailor, all of the city and county of
Philadelphia and state of Pennsylvania, have invented, or produced a
new and original design for a cooking stove and we do hereby declare
that the following is a full and exact description of the same.

On reference to the accompanying drawing which
forms a part of this specification.

Fig. 1 is a side view of our design for a cooking Stove.

Fig. 2. a front view, and

Fig. 3 a ground plan.

A is the bottom plate of the stove supported on the
legs B, B, B, B. C is one of the side plates having oven doors, a, and, c,
and fuel door, b, ornamented with designs as illustrated in the draw-
ing. D is the hearth plate, E the front plate having ornamental
doors, e, and, e', above the hearth. F is the top plate of the stove with
suitable openings for receiving the cooking utensils. G is the back
plate.

We claim and desire to secure by Letters Patent,
The combination of ornamental figures and forms represented in
the accompanying drawing forming together an ornamental design
for the plates of a cooking stove. In testimony whereof we have signed our
names to this specification before two subscribing witnesses.
